TELEVISION TRANSMITTER

Ray D. Kell, Princeton, N. J., assignor to Radio Corporation of America, a corporation of Delaware

Application July 6, 1944, Serial No. 543,667

17 Claims. (Cl. 178—7.2)

1
This invention relates to an improvement in television transmitters, and to the method of and apparatus by means of which a television transmitter may be operated to increase the sensitivity or effectiveness of operation, particularly under adverse light conditions.

In a conventional television system a television image pickup tube is provided which performs the function of translating an optical light image into a series of television image signals. This is accomplished by a scanning operation generally in which a cathode ray beam is caused to scan an electrode or target surface to convert an electrostatic charge image into a series of television image signals. As is well known to those skilled in the art, the scanning operation is accomplished by a bilateral deflection of the cathode ray beam in order that substantially all of the individual elemental areas of the target surface may be traversed by the cathode ray beam in a predetermined order. The cathode ray beam is generally deflected at a relatively rapid rate in one direction, conventionally the horizontal, and at a relatively slow rate in the transverse direction. The rapid deflection corresponds to the line deflection rate, whereas the slow deflection corresponds to the field deflection rate. Each time the cathode ray beam scans the target surface, a series of television image signals is generated for the field cycle. In conventional television systems this scanning operation is repeated regularly so that the target electrode is scanned for each vertical deflection of the cathode ray beam.

Interlaced scanning is frequently employed to reduce flicker effects and simultaneously to give the effect of improved detail, in which case the particular line elements scanned during one frame are displaced a predetermined amount from the line elements scanned during the immediately preceding frame cycle. The image or video signals generated by such scanning operation are a result of the presence of an electrostatic charge image on the target surface, and the intensity of the charge image, and accordingly the intensity of the produced television image signals is a function of the light intensity of the optical image projected on the television pickup tube.

Under very adverse light conditions the electrostatic charge image will, therefore, be rather feeble with the result that the produced television image signals will have very low intensity. Under normal operation of a television pickup tube there is a lower limit of light intensity at which a television image pickup tube can be operated

2
to produce satisfactory signals, but in some instances, it is desirable to operate a television pickup tube under conditions of less illumination than this lower limit.

5 According to the present invention, therefore, a provision has been made whereby television image signals of satisfactory intensity can be generated even though the light conditions are considerably subnormal. Since the charge image on the target surface in the television pickup tube is a function of the intensity of the amount of light projected upon the tube and in direct proportion to the length of time that intervenes between one cancellation of the charge condition **10** and the next succeeding cancellation, the intensity of the charge image may be increased by increasing the time interval. Therefore, under conditions when the light intensity cannot be increased and is considerably below that necessary to produce satisfactory television image signals, the present invention proposes the use of a system whereby the time interval during which the electrostatic charge image is produced may be increased by severalfold, thereby increasing the **15** intensity of the produced television image signals in like proportion.

Accordingly, and in a preferred form of the present invention, the scanning cathode ray beam is interrupted or discontinued for a predetermined number of vertical deflection cycles, thus permitting an appreciable electrostatic charge image to be formed. Later the cathode ray beam is permitted to be generated, and one vertical deflection cycle (or in an interlaced system, one **20** complete television frame) transpires, during which time the target surface is scanned by the cathode ray beam. Immediately at the conclusion of such scanning cycle, the cathode ray beam is again discontinued for a predetermined **25** length of time.

30 Such an operation naturally will result in producing a possible flicker condition at the receiver, the extent of the flicker being a function of the time interval between successive scanning cycles. Such an operation might be objectionable where **35** pure entertainment transmissions are desired, but where it is paramount to transmit a television image, even an appreciable amount of flicker might be tolerated, assuming an acceptable image from the standpoint of detail can be produced at the receiver.

40 Naturally, if there is any excessive amount of movement in the object area, and if the interval between effective scanning cycles is too great, the movement will be reproduced as a blur and, fur-

thermore, regardless of the amount of motion in the object area, some loss of detail may take place when an excessive amount of time intervenes between successive effective scanning cycles due to leakage laterally across the surface of the target area, i. e., due to neutralization or an averaging of adjacent electrostatic charges on the target surface. The interval between effective scanning cycles cannot, therefore, be increased indefinitely, but many scanning cycles can actually be omitted without any appreciable loss of detail and without an excessive or objectionable amount of blur. In fact, systems have been operated in which only one out of ten vertical scanning cycles is effective to produce television image signals, and in such operation the intensity of the produced image signals is materially increased, with the result that a much improved and clarified image is produced at the receiver over that which would be produced were each deflection cycle effective to produce image signals. In the absence of appreciable motion in the object area, the time interval between effective successive scanning cycles can be increased by increasing the lateral resistivity of the target surface upon which the electrostatic charge image is produced.

The present invention provides a system whereby the elimination or the formation of this scanning cathode ray beam is entirely automatic, and in which the time interval between effective scanning cycles is automatically controlled in accordance with a function of the light intensity of the object area. Accordingly, should the light intensity of the object area increase by a small amount, then the interval between effective scanning cycles is automatically decreased by one or more vertical deflection cycles.

It is, therefore, one purpose of the present invention to provide an improved television transmitting system wherein the effective sensitivity of the system may be materially enhanced.

Another purpose of the present invention resides in the provision of a method and means whereby a television transmitting system may be operated under light conditions which would be normally too low for a conventional television transmitting system.

A still further purpose of the present invention resides in the provision of means whereby the electrostatic charge image formed in a television image pickup tube is permitted to increase to a satisfactory charge level even under adverse light conditions.

A still further purpose of the present invention resides in the provision of means whereby the length of time intervening between one cancellation of the charge image in a television image pickup tube and the next succeeding cancellation may be increased to include two or more normal field deflection cycles.

A still further purpose of the present invention resides in the provision of means in a television transmitter whereby a scanning cathode ray beam in a television image pickup tube may be interrupted for one or more normal vertical deflection cycles to permit an increase in the charge image produced on a target surface.

Still another purpose of the present invention resides in the provision of means and apparatus whereby only predetermined vertical deflection cycles or field cycles are actually effective to produce television image signals.

Still another purpose of the present invention resides in the provision of means whereby the

lapse of time between successive effective scanning cycles may be automatically controlled in accordance with the light intensity of the object area.

Various other purposes and advantages of the present invention will become more apparent to those skilled in the art from the following detailed description, particularly when considered in connection with the drawing wherein:

Figure 1 shows a preferred form of the present invention; and

Figure 2 shows curves used in explaining the operation of the system.

Referring now to the drawing, and particularly Figure 1 thereof, there is shown a television image pickup tube 10 of the "Orthican" or low velocity storage type. Such a tube might include a light responsive surface 12 upon which an optical image may be projected by means of a lens system shown generally at 14. The tube also includes a very fine mesh screen 16, adjacent which is positioned a target surface 18 which may be in the form of an extremely thin glass plate. Intermediate the fine mesh screen 16 and the light responsive surface 12 is an accelerating anode or ring 20 which may be in the form of a conducting coating on the inside surface of the tube envelope. This conducting surface is maintained positive with respect to the light responsive surface by means of a source of potential 22.

When an optical image is projected upon the light responsive surface 12, photoelectrons will be emitted from that surface in proportion to the intensity of the light at any particular elemental area. These photoelectrons are accelerated in the direction of and are brought to focus upon the extremely thin target surface 18 by means of the accelerating ring or anode 20, and the focal condition is maintained by reason of the presence of an electromagnetic field produced by an electromagnetic coil 24 which surrounds the major portion of the entire television image pickup tube. The field produced by the coil is parallel to the axis of symmetry of the tube, and maintains proper relative position of the photoelectrons released from the surface 12.

The velocity at which the photoelectrons strike the surface of the target area 18 is sufficient to produce secondary electrons in a ratio of the order of three to one, and these secondary electrons are collected by the fine mesh screen 16 and are conducted outside the tube along conductor 26.

This operation produces a positive electrostatic charge image on the surface of the target area 18 adjacent the light responsive surface 12, but in view of the fact that the target surface is extremely thin, this charge is readily transferred to the opposite side of the target area 18. The target area or extremely thin glass plate 18 has some conductivity although, due to its extremely reduced thickness, the resistance between the faces of the target is many times less than the lateral resistance along the surface of the area 18. Accordingly, adjacent electrostatic charges are not neutralized, yet they may be readily transferred from the one side of the plate 18 to the other.

In the opposite end of the tube is located an electron gun structure which includes a cathode 28, a control electrode 30, a screen electrode 32, first anode 34 and second anode 36. The control electrode 30 is normally maintained negative with respect to the cathode 28, whereas the screen electrode 32 is positive with respect to the cath-

ode. The first and second accelerating anodes 34 and 38 have supplied thereto increasing positive potentials, and the electrostatic field produced at the adjacent ends of the first and second anodes may be used to assist in controlling the focal condition of the generated cathode ray beam at the plane of the target surface 18. Positioned within the first accelerating anode 34 is a cylindrical grid or screen 36 which is also maintained at a predetermined positive potential for 10 purposes which will be explained later. The proper operating potentials may be applied to the electrodes of the electron gun structure from any appropriate potential source which may, for example, be applied to terminals 40 and 42. Between these terminals a potentiometer or bleeder resistance may be connected in order that the relative potentials of the various electron gun structure electrodes may be properly chosen.

For deflecting the generated cathode ray beam in mutually perpendicular directions, a vertical deflection coil 44 is provided as well as a horizontal deflecting coil 46. The horizontal deflecting coil or coils are energized by a cyclically varying current of suitable wave form which is obtained from an appropriate horizontal deflection generator 50. Similarly, the vertical deflecting coil or coils are energized from a suitable vertical deflection generator 48. Inasmuch as the present invention is not concerned with the particular type of deflection generator used, these elements are shown schematically, and may be of any well known type to develop the desired deflection of the scanning beam. Such deflection generators in normal operation would be electrically 35 associated and interlocked with each other as taught by Bedford, for instance, in such a manner that a certain desired harmonic relationship would exist between the frequency of operation of the two deflection generators. These deflection generators, in accordance with the invention as disclosed in Figure 1, operate continuously to produce cyclically varying electromagnetic fields in opposed transverse directions within that portion of the tube immediately adjacent the location of the coils. Accordingly, when an electron beam is generated by the electron gun structure, the beam is caused to be displaced by the fields produced by the horizontal and vertical deflection coils, and as soon as the beam emerges from the 45 effects of these fields, the presence of the coil 24 causes the beam to be directed parallel to the axis of symmetry of the tube so that the scanning cathode ray beam is always directed against the target surface 18 in a direction normal to that surface.

When proper deflecting potentials or currents are applied to the deflecting coils 44 and 46, the cathode ray beam generated by the gun structure is caused to scan a predetermined area on the 50 target surface 18.

As previously described, the target electrode 18 has produced thereon an electrostatic charge image which is a replica of the optical light image. This charge image is in a positive direction, and the presence of the charge image produces a slight attraction force for the electrons of the scanning cathode ray beam. If no charge exists on a predetermined elemental area of the target surface 18, then under certain beam intensities and velocities, none of the electrons of the beam will be absorbed by that particular portion of the target area when it is scanned, and as a result, all of the electrons of the beam will be returned through the tube and will impinge upon the surface of the 75

first multiplier electrode 32 where secondary electrons will be produced. These produced secondary electrons will then be accelerated toward the cylindrical multiplier electrode 34 where additional secondary electrons may be produced. These produced secondary electrons will then be collected by the collector electrode or grid structure 36 and will then be conducted from the tube along the conductor 52. If the scanned portion of the target surface 18 has a positive charge image thereon, then a certain number of electrons of the scanning cathode ray beam will be absorbed thereby to cancel or neutralize the positive charge with the result that a lesser number of the electrons of the scanning cathode ray beam will be returned through the tube with the result that a smaller amount of current in the output conductor 52 will be present. Accordingly, as the electrostatic charge that is present on the electrode 18 is scanned by the cathode ray beam, the charge image is wholly or at least in part cancelled, and electrons not used for such cancellation will be returned through the tube, resulting in a current modulation of the returning cathode 25 ray beam. This current modulated cathode ray beam will then produce variations in current in the output conductor 52, and these variations in current or potential are the television image signals.

In order to cause the television pickup tube to operate at an optimum condition, it is desirable in some instances to alter the potential of the fine mesh screen 16 by a small amount in order to alter the average number of electrons that are permitted to reach the target surface 18. Under conditions of low light intensity, it has been found desirable to apply a slight positive potential of the order of one volt to the fine mesh screen 16; whereas under conditions of rather intense light conditions, it has been found desirable to operate the television pickup tube with a negative potential applied to the fine mesh screen 16 of the order of $\frac{1}{2}$ a volt. In order that the potential of the screen 16 may be altered within the desired limits, a potentiometer 54 is provided and a low potential difference is applied between the ends of the resistance element of the potentiometer. The mesh screen 16 is then connected by way of resistance 56 to a movable contact associated with the potentiometer.

The television image signals available from conductor 52 are then applied to appropriate amplifiers for increasing the intensity of the signals so that the image or video signals may be used to modulate a source of radio frequency energy in order that the signals may be transmitted to remotely located receivers. The transmitted video signals generated include, in addition to the image signals, appropriate synchronizing signals for maintaining the desired decrease of synchronous operation between the transmitter and the receivers. Since the present invention is not concerned with the particular amplifier or transmitting system utilized, such apparatus is represented schematically as apparatus 58 in the drawing.

With the apparatus as so far described, due to the periodic operation of the vertical and horizontal deflection generators 48 and 60, the cathode ray beam will scan the target area during each vertical deflection cycle and television image signals will be produced in accordance with the intensity of the optical light image projected on the television pickup tube. In accordance with the purpose of the present invention, the

able to operate the pickup tube in such a manner that satisfactory television image signals may be produced under extremely adverse light conditions, and the intensity of the produced image signals is increased by permitting an increased time interval within which the charge image present on the target electrode 18 is produced. In order to prevent a repeated cancellation or obliteration of the charge image for each vertical deflection cycle, the scanning cathode ray beam is interrupted for a predetermined number of vertical deflection cycles, and after a satisfactory charge image has been produced, the scanning cathode ray beam is then permitted to be generated during one vertical deflection cycle following which the beam is again interrupted.

For this purpose, a pair of tubes 60 and 62 are provided, and these tubes operate somewhat in the manner of a cathode coupled multivibrator. Each tube includes a cathode, a control electrode, and an anode, and the cathodes of the two tubes are connected to a point of fixed potential by a common cathode resistance 64. The control electrode of the tube 60 is connected to ground by way of grid resistance 66, and potential impulses of the vertical deflection frequency are applied to this control electrode by way of coupling condenser 68. It is preferable that these control impulses be of relatively short duration, and they may be derived, for example, from the vertical deflection generator 48. The wave forms of the voltage variations of vertical deflection frequency which are applied to the control electrode of tube 60 are represented, for example, by curve C of Figure 2. The anode of tube 60 is connected to terminal 72 to which a source of positive potential is applied, and the connection includes load resistance 74. The anode of tube 60 is coupled to the control electrode of tube 62 by coupling condenser 76, while the control electrode of tube 62 is connected by way of resistance 68 to the movable arm of a single-pole double-throw switch 78. With the switch in the lower position, the switch arm 78 is connected to a point of fixed potential by way of a variable resistance 82, the purpose of which will be described later. The anode of tube 62 may be connected directly to the terminal 72 and to the source of positive potential.

In operation, tubes 60 and 62 are alternately rendered conductive, and the value of the cathode resistance 64 is so chosen that the conducting interval of tube 62, i. e. the non-conducting interval of tube 60, corresponds to one vertical deflection cycle. It will be assumed that tube 60 is in a non-conducting condition, and at the conclusion of one vertical deflection cycle, tube 60 becomes conductive with the result that the potential at the anode of tube 60 changes rapidly in a negative direction due to current flow through the tube and due to the voltage drop across resistances 74. This produces a negative impulse on the control electrode of tube 62 by way of condenser 76 which drives the control electrode of tube 62 considerably negative with respect to its cut off potential as indicated by the vertical portion 84 of the curve B shown in Figure 2. The cut off potential of the tube 62 is indicated by the dotted line 86 associated with the curve. This negative potential gradually changes in a positive direction, and the rate of such change is determined by the value of the resistance included in the control electrode circuit of tube 62. If the resistance 82 is made small, the change of potential of the control electrode of tube 62 along the curved portion 88 of the curve B shown

in Figure 2 will be relatively rapid; whereas, if the resistance 82 is made relatively high, this change of potential in a positive direction will be much slower. During this change of potential, negative impulses of vertical deflection frequency continue to be applied to the control electrode of tube 60 and produce relatively short and somewhat low intensity positive impulses at the anode of tube 60 as indicated at 90 in the curve A of Figure 2. These same positive impulses appear at the control electrode of tube 62 as indicated at 92 in curve B. After the potential of the control electrode of tube 62 has gradually changed in a positive direction and approaches the cut off potential of tube 62, one of these positive impulses will render tube 62 conductive with the result that the increased current through the common cathode resistance 64 places a negative bias on tube 60, resulting in a non-conducting condition of tube 60, which enhances the positive potential applied to tube 62 as indicated by the short vertical portion 94 of the curve B shown in Figure 2. During the time that tube 60 is in a non-conducting condition, a positive potential or impulse, indicated at 96 in curve A, is produced at the anode of tube 60, and the duration of this impulse is regulated to correspond to the duration of one vertical deflection cycle. Accordingly, there will be present at the anode of tube 60 a series of positive impulses 96 (see curve A of Figure 2), the time duration of each of the impulses corresponding to one vertical deflection cycle. The time interval between impulses depends upon the amount of resistance included in the control electrode circuit of tube 62. These positive impulses, corresponding to one vertical deflection cycle, are then applied, by way of conductor 98, to a beam blanking amplifier 100 where their intensity is increased. After the desired degree of amplification, the impulses are then applied to the control electrode 30 of the electron gun structure by way of conductor 102.

The voltage variations applied to the control electrode 30 of the electron gun structure, therefore, have a wave form similar to the wave form of curve A of Figure 2 and this voltage variation results in the formation of a cathode ray beam only during the intervals of the positive impulses, represented at 96. During the time interval between these impulses, no cathode ray beam is generated. As stated above, the parameters of the circuit, and particularly the cathode resistance 64, are so chosen that the duration of the positive impulses corresponds to one vertical deflection cycle while the interval between impulses corresponds to one or more whole vertical deflection cycles, the number depending upon the amount of resistance included in the grid circuit of the tube 62. It is therefore possible to permit the production of a cathode ray beam for the duration of one vertical deflection cycle and to preclude the production of such a beam for the next succeeding several vertical deflection cycles. The positive charge image produced on the target surface 18 is permitted to accumulate to an appreciable value during the field cycles when no cathode ray beam is generated. During the vertical deflection cycle that a cathode ray beam is generated, the target surface 18 is scanned to produce image signals having an appreciable intensity, and the scanning beam cancels or neutralizes all, or an appreciable portion, of the charge image produced on the target electrode. If the light intensity of the

optical image is extremely low, then the value of resistance 82 may be increased to increase the time interval between operative scanning cycles; whereas if lighting conditions should improve slightly, the value of resistance 82 may be decreased to reduce the length of the inactive period by one or more vertical deflection cycles.

With the present invention as so far described, it is therefore possible to obtain television image signals from a television pickup tube in which the image signals have appreciable intensity even though the light intensity of the optical image is below that which would normally be required for the production of a satisfactory image signal series. The value of the resistance 82 may be conveniently manually controlled in accordance with existing light conditions.

There are instances when it is desirable to alter the inactive period automatically in accordance with variations with light intensity, and for this purpose a means is provided which is responsive to the light intensity of the object area. This means includes a light responsive cell 110 such as, for example, a photoelectric tube upon which light from the object area is projected by means of an optical system shown generally at 112. The current generated by the light responsive cell is supplied to a direct current amplifier 114 which may be of any appropriate design in order that the intensity of the currents generated by the light responsive cell may be appropriately increased. Two electron discharge tubes 116 and 118 are provided, each of which includes a cathode, a control electrode, and an anode. The control electrodes of these tubes are connected in parallel and are supplied with potentials from the direct current amplifier 114 in order that the potentials of the control electrodes may be varied with respect to their associated cathodes. The cathode of one tube, for example tube 116, and the anode of tube 118 are connected together and are in turn connected to a point of fixed potential as, for example ground; whereas, the anode of tube 116 and the cathode of tube 118 are connected together and in turn are connected to the upper terminal of the single-pole double-throw switch 78. When the switch 78 is in the upper position as indicated in the drawing, a resistance is therefore introduced between ground and the upper terminal of the selector switch 78, this resistance being, in fact, the plate resistance or internal impedance of tubes 116 and 118. In order that this resistance path will not be unilateral, the tubes 116 and 118 are reversely connected as indicated in the drawing. The application of a varying potential to the control electrodes of these tubes results in an alteration in the internal impedance of the tubes with the result that their effective resistance may be increased or decreased in accordance with the applied potentials. Since the applied potentials are derived from the direct current amplifier 114, which is energized from the light responsive tube 110, the extent of the potentials applied to the tubes 116 and 118 is a function of the light intensity of the object area. The polarity of the potentials derived from the direct current amplifier is so arranged that upon an increase in the light intensity of the object area, the effective impedance of the tubes 116 and 118 is decreased; whereas if the light intensity of the object area decreases, the effective impedance of the tubes 116 and 118 increases. By means of such a control it is therefore possible to automatically alter the 75

length of the interval between effective scanning cycles in accordance with the variations in the light intensity of the object area. Under conditions when the light intensity of the object area may vary during operation of the television pickup tube, such automatic control is desirable and the selector switch will be placed in the upper position as indicated in the drawing. If, however, lighting conditions remain substantially uniform or fixed, then the selector switch 78 may be placed in the lower position, and the number of ineffective cycles controlled manually by means of potentiometer 82.

From the above description it will therefore be apparent that a television pickup tube may be operated under extremely adverse light conditions yet the mode of operation may be so arranged that image signals of acceptable intensity may be produced by the pickup tube by the expedient of rendering the pickup tube ineffective for one or more vertical deflection cycles. Following the inactive period, the television pickup tube is rendered active or effective to produce television image signals for an interval corresponding to one vertical deflection cycle following which the tube is again rendered ineffective for a period of time inversely proportional to the light intensity of the object area.

Although the present invention is described somewhat in detail and although a more or less specific type of television pickup tube is shown and described herein, it is to be understood that various other television image pickup tubes could as well be employed so long as the tube involves an electron storage method of operation.

Various other alterations and modifications may be made in the present invention without departing from the spirit and scope thereof, and it is desired that any and all such modifications be considered within the purview of the present invention except as limited by the hereinafter appended claims.

Having described my invention, what I claim is:

1. A method of developing television signals which comprises forming electrostatic charges to represent the light values of a subject to be televised, electronically converting the produced charges into video signals at a pre-established conversion rate and controlling the time spacings between successive charge to signal conversions in accordance with the average brightness value of the subject being televised.

2. The method of operating a television pickup tube which comprises the steps of producing an electrostatic charge image of an object to be televised, generating a cathode ray beam, utilizing the generated cathode ray beam to convert the electrostatic charge image into electrical signals, and interrupting the generation of the cathode ray beam for predetermined time intervals each at least equivalent to the time to signal conversion intervals to permit the formation of an enhanced electrostatic charge image.

3. The method of operating a television pickup tube wherein an electrostatic charge image is formed from an optical light image which comprises the steps of generating a cathode ray beam, cyclically scanning the electrostatic charge image by the generated cathode ray beam to produce television image signals, and successively interrupting the generated cathode ray beam for a predetermined whole number of scanning cycles whereby a more intense electrostatic charge image may be formed.

4. The method of operating a television pickup

11

tube wherein an electrostatic charge image is formed from an optical light image which comprises the steps of generating a cathode ray beam, cyclically scanning the electrostatic charge image by the generated cathode ray beam to produce a series of television image signals, and successively interrupting the scanning operation for a predetermined whole number of scanning cycles whereby an enhanced electrostatic charge image may be formed between effective scanning cycles.

10

5. The method of operating a television pickup tube which comprises the steps producing an electrostatic charge image of an object to be televised, generating a cathode ray beam, deflecting the generated cathode ray beam in a predetermined pattern to convert the electrostatic charge image into electrical signals, interrupting the generation of the cathode ray beam for predetermined time intervals to permit the formation of an enhanced electrostatic charge image, and controlling the beam interruption time intervals in accordance with the light intensity of the object to be televised.

6. The method of operating a television pickup tube wherein an electrostatic charge image is formed from an optical light image which comprises the steps of generating a cathode ray beam, cyclically scanning the electrostatic charge image by the generated cathode ray beam to produce television image signals, successively interrupting the generated cathode ray beam for a predetermined whole number of scanning cycles to permit the formation of a more intense electrostatic charge image, and altering the interruption interval in accordance with the light intensity of the optical image.

7. A television transmitter including a television pickup tube having a target electrode, means for producing an electrostatic charge image on the target electrode corresponding to an optical light image, an electrode gun structure including an intensity control electrode for generating a cathode ray beam, beam deflecting means for causing the generated cathode ray beam to perform successive field scanning cycles of the target electrode to produce television image signals, and means for producing a voltage variation of rectangular wave form for modulating the potential of the control electrode to intermittently interrupt the cathode ray beam for time intervals corresponding to a predetermined whole number of field scanning cycles to permit the production of an intensified electrostatic charge image on the target electrode prior to each effective scanning cycle.

8. A television transmitter including a television pickup tube having a target electrode, means for producing an electrostatic charge image on the target electrode corresponding to an optical light image, an electrode gun structure for generating a cathode ray beam, beam deflecting means for causing the generated cathode ray beam to cyclically scan substantially the entire target electrode to produce television image signals corresponding to one television frame, and means for precluding the generation of the cathode ray beam for a time interval corresponding to a predetermined number of frame scanning cycles to permit the formation of an enhanced electrostatic charge image on the target electrode prior to the next effective scanning cycle.

9. A television transmitter including a television pickup tube having a target electrode, means for producing an electrostatic charge image on the target electrode corresponding to

12

an optical light image, an electrode gun structure including an intensity control electrode for generating a cathode ray beam, beam deflecting means for causing the generated cathode ray beam to cyclically scan the target electrode for each television field to produce television image signals, and means for modulating the potential of the control electrode to interrupt the cathode ray beam for a time interval corresponding to a predetermined whole number of field scanning cycles to permit the formation of an intensified electrostatic charge image on the target electrode prior to the next succeeding scanning cycle.

10. A television transmitter including a television pickup tube having a target electrode upon which an electrostatic charge image of an object area is adapted to be produced, means for cyclically scanning the target electrode by a cathode ray beam to convert the electrostatic charge image into a series of television image signals representing television fields, and means for repeatedly precluding the scanning of the target electrode for a predetermined number of whole field scanning cycles whereby the electrostatic charge image that is produced on the target electrode will be increased in intensity.

11. A television transmitter including a television pickup tube having a target electrode upon which an electrostatic charge image of an optical light image is adapted to be produced, means for cyclically scanning the target electrode by a cathode ray beam to convert the electrostatic charge image into a series of television image signals representing successive television fields, means for repeatedly precluding the scanning of the target electrode for a predetermined number of whole field scanning cycles following each effective field scanning cycle whereby the electrostatic charge image that is produced on the target electrode will be increased in intensity, and means for altering the intervals during which the scanning operation is precluded by one or more whole field scanning cycles.

12. A television transmitter including a television pickup tube having a target electrode upon which an electrostatic charge image of an object area is adapted to be produced, means for cyclically scanning the target electrode by a cathode ray beam to convert the electrostatic charge image into a series of television image signals, means for intermittently interrupting the scanning of the target electrode, each interruption interval corresponding to a predetermined number of whole scanning cycles whereby the electrostatic charge image that is produced on the target electrode will be increased in intensity between effective scanning cycles, and means responsive to the light intensity of the object area for altering the duration of the interruption intervals.

13. A television transmitter including a television pickup tube having a target electrode upon which is produced an electrostatic charge image of an optical light image, an electron gun structure for generating a scanning cathode ray beam, means for deflecting a generated cathode ray beam in predetermined directions in order to produce successive television frame scanning cycles to scan the target electrode to convert the electrostatic charge image into television image signals and means to permit the generation of a cathode ray beam during certain frame scanning cycles, the interval between cathode ray beam generation intervals corresponding to one or more complete frame scanning cycles and the dura-

tion of each cathode ray beam generation interval corresponding to at least one frame scanning cycle, whereby the intensity of the electrostatic charge image present on the target electrode at the time the target electrode is scanned by the generated cathode ray beam may be intensified.

14. A television transmitter including a television pickup tube having a target area upon which is produced an electrostatic charge image of an optical light image, an electron gun structure for generating a scanning cathode ray beam, means for deflecting a generated cathode ray beam in substantially mutually perpendicular directions in order to scan the target area to convert the electrostatic charge image into television image signals corresponding to a television field, means to permit the formation of a cathode ray beam during certain field scanning cycles, the time interval between formations of the cathode ray beam corresponding to one or more complete field scanning cycles and the duration of the formation of the cathode ray beam corresponding to at least one field scanning cycle, and means for altering the time interval between successive formations of the cathode ray beam, whereby the intensity of the electrostatic charge image present on the target area at the time the target area is scanned by the formed cathode ray beam may be increased in intensity.

15. A television transmitter including a television pickup tube having a target electrode upon which is produced an electrostatic charge image of an optical light image, an electron gun structure for producing a scanning cathode ray beam, means for cyclically deflecting a produced cathode ray beam in substantially mutually perpendicular directions in order to scan the target electrode to convert the electrostatic charge image into television image signals, means to repeatedly prevent the production of a cathode ray beam during certain scanning cycles, the intervals that production of the cathode ray beam is prevented corresponding to one or more complete scanning cycles and the duration of the producing of the cathode ray beam corresponding to at least one scanning cycle, and means for altering the interval between successive productions of the cathode ray beam by one or more complete scanning cycles, whereby the intensity of the electrostatic charge image present on the target electrode may be enhanced between the production intervals.

16. A television transmitter including a television pickup tube having a target electrode, means for producing an electrostatic charge image on the target electrode corresponding to an optical light image of an object area to be televised, an electron gun structure including a beam intensity control electrode for generating a cathode ray beam, beam deflecting means for causing the generated cathode ray beam to cyclically scan the target electrode to convert the electrostatic charge image into television image signals corresponding to successive television fields, means for intermittently preventing the generation of the cathode ray beam for a predetermined number of field scanning cycles and for intermittently permitting the generation of the cathode ray beam for a time interval corresponding to one field scanning cycle whereby the intensity of the electrostatic charge image may be increased between each effective scanning cycle, and means for altering, by one or more field scanning cycles, the time interval during which the generation of the cathode ray beam is prevented in accordance with the light intensity of the object area to be televised.

17. A television transmitter including a television pickup tube having a target electrode, means for producing an electrostatic charge image on the target electrode corresponding to an optical light image of an object area to be televised, an electron gun structure including a beam intensity control electrode for generating a cathode ray beam, beam deflecting means for causing the generated cathode ray beam to cyclically scan the target electrode to convert the electrostatic charge image into television image signals, means for producing a voltage variation of substantially rectangular wave form, means to apply the produced voltage variation to the intensity control electrode to intermittently prevent and permit the generation of a cathode ray beam in synchronism and in phase with the scanning operation whereby the intensity of the electrostatic charge image may be increased between effective scanning cycles, and means for altering in accordance with the light intensity of the object area to be televised, the time interval during which the generation of the cathode ray beam is prevented.
